UNITED STATES PATENT OFFICE.

JAMES C. SHOUP, OF ST. LOUIS, MO., ASSIGNOR OF SIX-TENTHS TO JOSEPH FRANKLIN AND GEORGE M. WRIGHT, BOTH OF SAME PLACE.

AUTOGRAPHIC REGISTERING APPARATUS.

SPECIFICATION forming part of Letters Patent No. 286,560, dated October 9, 1883.

Application filed December 19, 1882. (No model.)

To all whom it may concern:

Be it known that I, JAMES C. SHOUP, a citizen of the United States, and a resident of St. Louis, State of Missouri, have invented an Improved Autographic Registering Apparatus, 55 of which the following is a specification.

The essential objects of my invention are to provide an improved apparatus to register autographic writings, marks, signs, and impressions of all kinds, the original of which can be used and kept apart by the writer, while the duplicate or fac-simile of the same is secretly preserved, so that it cannot be improperly or unlawfully tampered with without 15 the fact being indicated or leading to detection. This invention will be of great use and benefit to all who desire to make or keep copies, and have at all times a faithful, true, and correct transcript or record of transactions had 20 of the nature referred to. I accomplish the said objects by the mechanism illustrated in the accompanying drawings, of which—

Sheet I, Figure 1 is a side elevation, the hinged door of the casing being broken away 25 to better show a side view of the interior mechanism. The arrows indicate the direction in which the reels and ribbon strips move. Fig. 2 is a top or plan view, showing the tablet upon which the writing is done, the plate 30 bearing upon the margins of the strips, and the window for permitting inspection of the duplicate strip, which is stored upon the receiving-reel. Detail parts are shown where the frame-plates are broken away. Sheet II, 35 Fig. 3 is a longitudinal central sectional elevation. Figs. 4 and 5 are respective cross-sectional elevations, the former being taken on line 4 4, and the latter figure on line 5 5, of Fig. 3. Fig. 6 is an enlarged detail section of 40 the tablet-face and its ribbon strips, and Fig. 7 a detail view of the brake to control the reels.

Similar letters of reference refer to similar parts throughout the several views.

45 The frame-work consists of two counterpart sides or metal frames, A A', secured apart by brace-rods, as indicated in the drawings. The brace-rods a a' a' serve as bearings, upon which the hollow shell of the reels turn.

50 B B' B' are the reels or spools, B being the receiving-reel, upon which the strip or ribbon

having the fac-simile or record is to be wound and stored, as will hereinafter appear. B' B' are the dispensing reels or spools, upon which the strips are wound, to be given out as required. Each reel, as herein shown, consists of a hollow shell, b, from which, at each end, project the disk-heads b' b'. Each reel, as stated, turns upon its proper bearings, and, when occasion requires, can be slipped off or 60 on, for purposes hereinafter stated.

c c' represent the respective strips or ribbons, or their equivalent, upon which the writing or impression is to be made. The reels B' B' are supplied with the requisite 65 strips of paper, and then adjusted upon their bearings. The strip c comes from the reel B', and that of c' comes from the reel B', and the loose ends of both said strips c c' are then passed, the one on top of the other, between the 70 two guide-rollers d d'. (See Figs. 1, 3.) The two rollers d d' turn easily in the frame-work and serve to direct the passage of the two strips c c' to and over the top face, X, of the apparatus. Further, both strips c c' next pass 75 between the gripping-rollers at d' d'. The upper roller, d', is preferably of rubber, and by means of the side springs at d' is made to bear upon the strips c c', and thus grip them, so that upon the movement of the lower strip, those 80 above will be carried along with it. The roller d' is covered with a semi-curved plate or housing, d'', the front face of which is made to a knife-edge, d'', whereby the top strip, c, can be readily cut off. The under or bottom strip, c', is 85 continued or passed under a glass or window face, (marked X'), which is inclined, so that the record cannot readily be seen from behind the user, as shown in Figs. 2, 3, 5. From thence the said bottom strip, c', still farther 90 passes over the guide-roller e, and finally said bottom strip is wound upon the storing-reel B (see Figs. 1 and 3)—that is to say, the bottom strip extends from the dispensing-reel B' to the storing-reel B. It will be seen that by 95 turning the crank E, attached to the receiving-reel B, all the said reels are made to turn in the same direction, and both the strips c c' are moved over the tablet X and passed between the rollers d' d', one downward under 100 the window to the storing-reel, and the other outward above the window, to be cut off by

the knife-edge d^2 . The reels $B' B^2$, carrying a plurality of strips, are made to give out the same length of strip taken in by storing-reel B. The under strip of the series, after passing 5 guide-rolls $d' d'$, over the tablet X, and between grip-rollers $d^2 d^2$ and over guide-roller e, is attached to storing-reel B and is wound up by moving crank E.

F is a stop applied to bear directly on the 10 periphery of the receiving-reel B, (see Figs. 1, 7,) to prevent slackening and reverse turning on the part of the said reel, and at f a spring-brake is applied to bear against the sides of the two dispensing-reels $B' B^2$, and insure a 15 uniform tension on the strips and movement on the part of the reels.

It is essential to carry out my purpose that a transfer medium be used in combination with the aforesaid top and bottom strips, $c c'$. 20 g represents this transfer medium, and consists of a strip of carbon paper or ink-ribbon, or its equivalent, for taking a copy of writing by pressure. This carbon or ink strip I arrange as follows:

25 $H H'$ are the two small reels, arranged as shown. Upon these reels the strip is arranged, so that it can be unwound from the reel H' and be wound upon the other reel, H. The reel H, by its bevel-gear h , meshes with a like 30 bevel-gear, h' , the latter having one end of its shaft extending outside the frame-work and casing, and is operated by thumb-nut h^2 . Thus both reels $H H'$ are made to turn in the same direction. The strip g is first coiled as a supply—say upon reel H' . The other end of said 35 strip is then passed upward in a vertical direction over the side rolls, across the tablet-face, between the respective top and bottom strips, $c c'$, as shown. From thence said strip g passes vertically downward, and is finally 40 secured to the remaining reel, H, all clearly shown in Fig. 4. By simply turning the thumb-nut h^2 , the reels $H H'$ are revolved, the strip g winding upon reel H and unwinding 45 from reel H' , and in doing so a fresh supply or new portion of the transfer-strip g is brought between the upper and lower strips, $c c'$, and the old or worn-out portion of strip g is carried to reel H and wound up. The changing 50 of strip g , as described, is only done when it is necessary to obtain clearness of impression upon the record-strip c' , or when that portion over the tablet-face has been worn out. The carbon strip g is held stationary so long as it 55 can be used to make clear impressions or copies, and is moved transversely across the tablet-face, between the strips $c c'$, whenever a change is required to give a clear impression, which can be determined by inspection of the record- 60 copy under the window.

In order to provide means for removing the storing-reel B, with its record or strip c' , as also the reels $B' B^2$, in a lawful manner, for obvious purposes, I have hinged the under portion of one of said side frames (marked I) to the upper portion of said side frame, as shown in Fig. 1. By unscrewing thumb-nuts $i^2 i^2$ from

the tie-rods $z z'$, the hinged frame I is free to be turned upward sufficiently to leave each reel $B B' B^2$ free to be removed from the apparatus—that is to say, when the reel B is to be removed, with its record, the operator first breaks the continuity of the record-strip c' , and then slips the said reel, with its coil, from off its bearings. In like manner the remaining reels, 75 $B' B^2$, can be slipped off from their bearings for repairs and to replace the exhausted strips, &c.

The apparatus thus made is contained inside of a suitable casing or box, J. This casing J 80 may have the hinged door J', which can be properly fastened or locked. Along the casing J are secured strips or flanges of metal, j , which project or lap over the outer edges of the paper strips, (see Fig. 2,) and like metal 85 flanges, j' , lap over and hide the window edges.

The complete apparatus thus constructed, as shown and described, is operated and used in the following manner. The writing is done upon the top sheet or strip, c . Suppose the 90 writings, &c., to be as follows: "2nd National Bank cftcts., \$2,000.00; checks, \$1,500.00; total, \$3,500.00. James C. Shoup." At the same time that the writing is made upon the top strip, c , an exact duplicate or fac-simile is 95 also made upon the bottom strip, c' . The crank E is next turned by the operator, which revolves the storing-reel, and this winds up the record-strip, which in passing the grip-rollers causes them to revolve and draw the 100 upper strip, with the lower strip, over the face of the tablet from off the dispensing-reels simultaneously until the writing upon the upper strip is a little beyond the knife-edge, when that portion of the upper strip, with its 105 writing, is torn off, for such uses as it may be applicable to. The fac-simile remains inside the apparatus upon the storing-reel. Successive written orders, receipts, messages, &c., can be made, and their exact counterpart may be 110 kept as a record for future use.

It will be observed that the dispensing reels or spools, the storing-reel, the guide-rolls, and the gripping-rolls are independently mounted in the frame without connection by gearing of 115 any kind, and that by reason of this the dispensing-spools give out just the length of strips required by the draft of the storing-reel, thereby always keeping all the strips taut.

What I claim, and desire to secure by Letters Patent, is—

1. In an autographic registering apparatus, the combination of the dispensing-spools and a storing-reel, each mounted upon its shaft independent of the others, the dispensing-spools being moved to give out a plurality of strips by reeling up the registry-strip, as herein described.

2. In an autographic registering apparatus, 130 the combination of dispensing-spools, a storing-reel, and friction-rolls, as $d^2 d^2$, mounted in the frame independent of each other, and moved in unison to give out a plurality of

strips and reel up one of them by moving the registry-reel, as hereinbefore described.

3. In an autographic registering apparatus, the combination, with the independently-mounted dispensing-spools, storing-reel, and grip rolls, of the reels and guide-rolls for moving the transfer-paper at right angles with the strips and across the tablet, as herein described.

10 4. In an automatic registering apparatus, the combination hereinbefore described of the dispensing-spools, guide-rolls, grip-rolls, and storing-reel, all independently mounted in the frame, substantially as and for the purposes set forth.

15 5. In an autographic apparatus, the combination hereinbefore described of the frames A A', brace-rods a a' a'', hollow drums or spools B B' B'', and tie-rods z z', for the purpose specified.

6. In an autographic apparatus substantially such as described, the combination, with the rigid frame, brace-rods, and tie-rods, of the hinged frame I, for the purpose specified.

7. In an autographic registering apparatus, 25 the combination of the independently-mounted dispensing-spools and storing-reel, and brakes for causing resistance to the forward movement of the dispensing-spools, and a stop to prevent the backward movement of the storing-reel, whereby the train is moved by rotating the storing-reel to wind up the registry-strip, and a tension, maintained as herein specified.

8. In an automatic registering apparatus, 30 35 the combination hereinbefore described of dispensing-spools, guide-rolls, tablet-face, gripping-rolls, inclined window-face, and storing-reel, substantially as and for the purposes set forth.

In testimony of said invention I have hereunto set my hand.

JAMES C. SHOUP.
